UNITED STATES PATENT OFFICE.

ARTHUR ATWATER KENT, OF ARDMORE, PENNSYLVANIA.

RADIO APPARATUS.

Application filed June 19, 1924. Serial No. 720,890.

- My invention relates to radio receiving apparatus and more particularly to structure for mounting the various elements and parts upon a panel to form a compact unit.
- 5 In accordance with my invention I provide a plate or panel of sheet metal having secured thereto an element of such character and so positioned as to stiffen the plate or panel to hold it flat and prevent it from 10 bowing, buckling or warping; and upon the panel and stiffening element are mounted the various parts or devices of the receiving apparatus, some of them operable from the front of the panel, and all forming with 15 the panel and its stiffening member a unit suitable for application to a cabinet or box.
- Further in accordance with my invention the panel structure is connected to earth or counterpoise capacity, and particularly when there is supported thereby one 20 or more radio frequency variable tuning devices requiring the approach of the body or hand of the operator.
- My invention resides in the features of 25 structure, combination and arrangement of parts of the character hereinafter described and claimed.
- For an illustration of one of the various forms my invention may take reference is 30 to be had to the accompanying drawings in which:
- Fig. 1 is a front elevational view of a cabinet having my structure applied thereto.
- Fig. 2 is a horizontal sectional view, 35 partly in plan, on the line 2—2 of Fig. 1.
- Fig. 3 is a vertical sectional view, parts in elevation, taken on the line 3—3 of Fig. 2.
- Figs. 4, 5 and 6 are vertical sectional 40 views, partly in elevation, taken, respectively, on the lines 4—4, 5—5 and 6—6 of Fig. 2.
- Fig. 7 is a view in perspective of the rear of the panel structure.
- Fig. 8 is a diagrammatic view of a 45 circuit in which the various parts supported by the panel structure are connected.
- Fig. 9 is a fragmentary front elevational view of the panel having an index member applied thereto.
- Fig. 10 is a vertical sectional view taken 50 on the line 10—10 of Fig. 9.
- Fig. 11 is a perspective view of the index element.
- 55 Referring to the drawings, 1 is the bottom of a housing, cabinet or box of wood, or any other suitable material, having the back 2, ends 3, 3, top member 4, preferably permanently attached to the ends 3, 3, and the top or cover 5 hinged to the back 2 at 60 6. Overlying the bottom 1 and underlying the top 4 are the strips 7 to which are secured by screws 8 the sheet metal plate or panel P of iron, steel, aluminum, brass or other similar suitable material. Secured to the panel P adjacent and substantially parallel to its lower edge is the ledge or stiffening member L preferably of sheet metal, having the integral flange 9 spot welded or otherwise secured to the panel P. 70 The member L with its flange 9 is in effect an angle member which, particularly due to the width of the ledge L, stiffens the panel P as a whole, preventing it from bowing, buckling or warping, and causing 75 it to remain flat permitting easy fastening by screws 8 to the box or cabinet structure, without bowing or buckling between the screws.
- There are mounted upon the panel P and 80 the ledge L various parts or devices of the radio receiving apparatus. In the example illustrated the receiving apparatus comprises two stages of radio frequency amplification, a detector and two stages of 85 audio frequency amplification.
- In Fig. 8 there is shown by way of example a diagram of the circuit arrangement. The antenna A is connected to binding post 48, which in turn is connected to the movable switch blade 49 coacting with several 90 contacts 50 connected respectively through suitable taps to different points in the winding 10, whose one terminal connects through binding post 51 to earth or counter-capacity 95 E and whose other terminal connects to the grid of the tube V. The switch comprising the movable contact 49 and contacts 50 is mounted upon the panel P. Shunting the inductance 10 is the variable tuning condenser C whose terminals are connected to the grid-filament circuit of the radio frequency amplifier tube V in whose anode circuit is connected the primary winding 11 of the radio frequency transformer T whose 105 secondary 12, shunted by the variable tuning condenser C¹, is connected to the grid-filament circuit of the second radio frequency amplifier tube V¹ in whose anode circuit is the primary 13 of a radio frequency transformer T¹ whose secondary 14, shunted by 110 the variable tuning condenser C², is con-

5 nected on the one hand to the filament of the detector tube V^3 and at its other terminal to the grid of the tube V^2 through the grid condenser K shunted by the grid leak re-
 10 sistance 15. In the anode circuit of the tube V^2 is the primary 16 of an audio frequency transformer T^2 , shunted by the bypass condenser K^1 . The secondary 17 is connected to the grid circuit of the audio frequency amplifier tube V^3 in whose anode circuit is the primary 18 of an audio frequency transformer T^3 whose secondary 19 is connected in the grid circuit of the second audio frequency amplifier tube V^4 in whose
 15 anode circuit are the binding posts 20 and 21 for connection to a telephone instrument or loud speaker. One terminal of all the filaments of the five tubes is connected to the conductor 22 connecting with the binding post 23 with which are connected the positive terminal of the A battery and the negative terminal of the B batteries. The other terminal of the filaments of the tubes V and V^1 is connected to the conductor 24
 20 which connects through the variable resistance or rheostat 25 and switch 26 with the binding post 27 connecting with the negative terminal of the A battery. The binding post 27 connects also through the switch 26 and
 25 the variable resistance or rheostat 28 with the conductor 29 connecting with the remaining terminals of the filaments of the tubes V^2 , V^3 and V^4 . The binding post 30 connecting with the positive terminal of the
 30 low voltage B battery connects through conductor 31 with the anode circuit of the detector tube V^2 ; and the binding post 32 connecting with the positive terminal of the high voltage B battery connects through conductor 33 with the anode circuits of the tubes V , V^1 , V^3 and V^4 .
 35 The conductor 24 as shown is connected to the earth or counterpoise capacity E and the panel structure, either the panel P itself or the ledge member L, is connected to earth or counter capacity E, as indicated by conductor 34.

40 Each of the conductors C, C^1 and C^2 comprises, as indicated in Fig. 4, the rotatable armature plates 35 co-acting in well known manner with suitable stationary armature plates 36, and carried upon a rotatable shaft having bearings carried by the supporting members 37 and 38 to which the member 37
 45 is secured by screws 39 to the rear face of the panel P, the shaft extending freely through the panel and having secured upon its outer end the dial 40 having the operating handle or knob 41.

50 The inductance 10 is wound upon the cylinder 42 of insulating material, which latter is supported by brackets 43 upon the condenser member 38. The radio frequency transformers T and T^1 are similarly supported upon the corresponding members 38

of the condensers C^1 and C^2 respectively. As indicated, the axes of the inductance 10 and transformers T and T^1 are all disposed at right angles to each other.

55 There are accordingly supported directly upon the metallic plate P itself the three units, C,10, C^1 ,T and C^2 , T^1 .

60 Between the first two of said units is disposed a socket unit for the tube V, said unit comprising a base member 44 of insulating material secured by screws 45 to the metallic ledge L. As indicated, the base or supporting member 44 overhangs or extends beyond the edge of the ledge L in a horizontal direction. Secured upon the base 44 is the socket sleeve 46 in which is received and held the tube V, by structure well understood in the art, with the tube terminals coming into register with suitable yielding spring terminals 47. The binding post 48, carried by the base member 44, is adapted to be connected to the antenna, as by lead extending to the antenna through the hole 52 in the rear wall 2 of the box.

65 The conductor 24 may connect, for example, with the binding post 51, to which may be connected a lead extending to earth or ground E through the hole 53 in the rear wall 2 of the cabinet.

70 Similarly, between the units C^1 ,T and C^2 , T^1 is secured by screws 45 upon the ledge member L the base 54, preferably of insulating material, provided with the socket shell 55 for the tube V^1 .

75 To the right of the condenser C^2 , Fig. 2, there is secured by screws 56 upon the front face of the panel P the base 57 of insulating material, carrying the aforesaid rheostat resistances 25 and 28, and the A battery switch 26. The movable contact of the rheostat 25 controlling the filaments of the tubes V and V^1 , is rotatable by the rotatable knob or handle 58 carried by the base 57; and similarly, the movable contact of the rheostat 28, controlling the filaments of the three remaining tubes, is rotatable by the knob or handle 59 mounted upon the base 57.

80 Secured to and preferably overhanging the ledge L, to the right of the unit C^2 , T^1 , is the base 60 of insulating material held to the ledge L by screws 61. Upon this base are supported the socket sleeves 62, 63 and 64 for the tubes V^2 , V^3 and V^4 respectively; there are also mounted upon the base 60 the grid leak resistance 15 and the audio frequency transformers T^2 and T^3 disposed in suitable casings. Mounted upon the member 60 are the binding posts 20, 21, 23, 27, 30 and 32, the A and B battery leads extending through the hole 65 and the telephone or loud speaker leads through the hole 66 in the rear wall 2 of the cabinet. As indicated in Figs. 4, 5 and 6 the filament and other conductors indicated in Fig. 8 may be disposed on the underside of the ledge L

and connected to the several parts and devices in the manner indicated in the diagram.

In the angle between the ledge L and its flange 9 is disposed the bypass condenser

5 K' as indicated in Figs. 3 and 5. It is held by a metal bracket or clip 67 held by screw 68 to the ledge L. This screw, making metallic contact with the ledge L, which in turn is metallically connected with the panel

10 P, may be utilized for making the ground connection with the panel P as by securing by a screw 68 a conductor extending to and connecting with the aforesaid ground binding post 51.

15 Referring to Figs. 9, 10 and 11 there is shown a pointer or index 69 of German silver or other metal or material having the rearwardly extending prongs 70 extending through holes in the panel P and then bent

20 parallel to the panel as indicated in Fig. 10, for holding the index 69 in fixed position upon the panel. The lower end of the index 69 is disposed adjacent each of the condenser or other dials 40 each of which carries suitable markings or graduations co-acting with

25 the index mark 71 on member 69 for assisting in adjustment and repeating adjustments of the condensers or other similar variable instruments.

30 From the foregoing description it is apparent that all of the parts and devices of the receiving apparatus are supported upon the panel structure, some of them upon the panel proper and some upon the ledge or 35 stiffening member. By raising the cover 5 access to the interior of the cabinet is had and upon disconnecting the antenna, ground, battery and telephone leads the entire receiving apparatus may be removed as a unit 40 upon removal of the screws 8.

The panel structure is stiff and remains flat, whereby it may with facility be applied to a cabinet or the like and whereby it rigidly supports all of the instruments, parts 45 or devices and maintains them strictly in predetermined and fixed relations with respect to each other. Furthermore, the approach of the body or hand of an operator as to any of the handles or knobs 41, 58 and 59 produces no capacity effect, especially upon the radio frequency circuits, because of the grounding of the metallic panel structure or because of its connection with suitable part of the radio frequency circuit or 55 circuits.

A panel P of metal is further of advantage in that there may be applied thereto, decorative finishes producing mottled, frosted and other effects not suitable to or convenient with panels of wood or other non-metallic materials.

What I claim is:

1. The combination with a housing, of a 35 panel structure forming a detachable wall of said housing and comprising a sheet metal

panel and a member secured thereto and having substantial extent normal thereto for stiffening said panel substantially throughout its entire extent, and radio receiving apparatus carried by said panel structure within said housing and removable as a unit with 70 said panel structure.

2. The combination with a housing, of a panel structure forming a wall of said housing and comprising a sheet metal panel and a member secured thereto and having substantial extent normal thereto for stiffening said panel substantially throughout its entire extent, radio receiving apparatus carried by said panel structure within said housing and removable as a unit with 75 said panel structure, and a connection from said panel structure and said receiving apparatus extending to ground.

3. The combination with a housing, of a panel structure forming a detachable wall of said housing and comprising a sheet metal panel and a member secured thereto and having substantial extent normal thereto for stiffening said panel substantially throughout its entire extent, and radio receiving apparatus all of whose devices are carried solely by said panel structure within said housing and are removable as a unit with 80 said panel structure.

4. The combination with a housing, of a panel structure forming a wall thereof and comprising a sheet metal panel and a member secured thereto and having substantial extent normal thereto for stiffening said panel substantially throughout its entire extent, said member forming a ledge upon said panel within said housing, and radio receiving apparatus comprising devices carried respectively by said panel and said ledge with 85 in said housing and removable as a unit with said panel and ledge.

5. Radio receiving apparatus comprising panel structure comprising a sheet metal member and a sheet metal ledge having a flange intimately united with said panel for stiffening said panel throughout substantially its entire extent, tuning apparatus carried by said panel structure, and an electrical connection from said panel structure to a 90 part of said tuning apparatus.

6. Radio receiving apparatus comprising panel structure comprising a sheet metal panel and a member secured thereto and having substantial extent normal thereto for stiffening said panel throughout substantially its entire extent, tuning means carried by said panel, and vacuum tube mounting structure carried by said member.

7. Radio receiving apparatus comprising a sheet metal panel, metal ledge structure secured thereto and stiffening said panel throughout substantially its entire extent, an insulating member secured to said ledge member and overhanging said ledge member,

- and a tube socket carried by said insulating member.
8. Radio receiving apparatus comprising a sheet metal panel, metal ledge structure secured thereto and stiffening said panel throughout substantially its entire extent, an insulating member secured to said ledge member and overhanging said ledge member, a tube socket carried by said insulating member, and tuning means secured to said panel. 10
9. Radio receiving apparatus comprising a sheet metal panel, metal ledge structure secured thereto and stiffening said panel throughout substantially its entire extent, an insulating member secured to said ledge member and overhanging said ledge member, a tube socket carried by said insulating member, and a tuning unit comprising a winding and a variable condenser carried by said panel. 15
10. Radio receiving apparatus comprising a sheet metal panel, metal ledge structure secured thereto and stiffening said panel throughout substantially its entire extent, an insulating member secured to said ledge member and overhanging said ledge member, a tube socket carried by said insulating member, and tuning devices carried by said panel on opposite sides of said socket. 20
11. In radio receiving apparatus, the combination with panel structure comprising a sheet metal panel member and sheet metal ledge structure secured thereto and having substantial extent substantially normal to the plane of said panel member, of radio receiving apparatus all of whose devices are carried by said panel structure, part by said panel member and part by said ledge structure. 25
12. In radio receiving apparatus, panel structure comprising a metal panel, metal ledge structure welded thereto and having substantial extent substantially normal to said panel for stiffening said panel, and radio receiving devices carried respectively by said panel and ledge structure. 40
13. In radio receiving apparatus, panel structure comprising a metal panel, metal ledge structure welded thereto and having substantial extent substantially normal to said panel for stiffening said panel, a member of insulating material secured to said ledge structure and over-hanging the same, and a vacuum tube holder carried by said last named member. 45
14. In radio receiving apparatus, panel structure comprising a metal panel, metal ledge structure welded thereto and having substantial extent substantially normal to said panel for stiffening said panel, a member of insulating material secured to said ledge structure and over-hanging the same, a plurality of vacuum tube holders carried by said last named member, and an inter-tube transformer carried by said last named member. 50
15. Radio receiving apparatus comprising a housing, a sheet metal panel constituting a detachable wall of the housing, sheet metal structure extending longitudinally of the panel normally thereto for stiffening it substantially throughout its entire length, an internal flange on such sheet metal structure welded upon said panel, and devices of radio receiving apparatus carried respectively by said panel and said sheet metal structure. 55
